US00D825166S

(12) **United States Design Patent** (10) Patent No.: **US D825,166 S**
(45) Date of Patent: ** *Aug. 14, 2018

(54) **SHOE INSERT**

- (71) Applicant: **LFRJ, LLC**, West Hollywood, CA (US)
- (72) Inventors: **Robert Joseph**, West Hollywood, CA (US); **Lawrence Edward Feigen**, West Hollywood, CA (US)
- (73) Assignee: **LFRJ, LLC**, West Hollywood, CA (US)
- (*) Notice: This patent is subject to a terminal disclaimer.
- (**) Term: **15 Years**
- (21) Appl. No.: **29/577,849**
- (22) Filed: **Sep. 15, 2016**
